UNITED STATES PATENT OFFICE

145,990

DESIGN FOR A LUBRICATING EQUIPMENT CABINET

John Tjaarda, Grosse Pointe Shores, Mich., assignor to Stewart-Warner Corporation, Chicago, Ill., a corporation of Virginia

Application November 21, 1945, Serial No. 123,949

Term of patent 14 years

(Cl. D52—2)

To all whom it may concern:

Be it known that I, John Tjaarda, a citizen of the United States, residing at Grosse Pointe Shores, in the county of Wayne and State of Michigan, have invented a new, original, and ornamental Design for a Lubricating Equipment Cabinet, of which the following is a specification, reference being had to the accompanying drawing, forming part thereof.

The figure is a perspective view of a lubricating equipment cabinet, showing my new design. The cabinet is symmetrical about its longitudinal center plane.

I claim:

The ornamental design for a lubricating equipment cabinet, substantially as shown and described.

JOHN TJAARDA.
